UNITED STATES PATENT OFFICE

160,403

CHILD'S CLOTHES RACK

June L. Lenz, Fort Washington, Md.

Application August 16, 1949, Serial No. 4,540

Term of patent 14 years

(Cl. D33—8)

To all whom it may concern:

Be it known that I, June L. Lenz, a citizen of the United States, residing in Fort Washington, State of Maryland, have invented a new, original, and ornamental Design for a Child's Clothes Rack, of which the following is a specification, reference being had to the accompanying drawing, forming part thereof.

I claim:

The ornamental design for a child's clothes rack, as shown.

JUNE L. LENZ.
